CONCRETE MIXER

Daniel Jeremiah Price, Mullen, Tex.

Application April 6, 1932. Serial No. 603,662

3 Claims. (Cl. 83—73)

My invention relates generally to mixers and particularly to devices for mixing into usable form, mineral aggregates, and water, and the like, whereby to form building material, concrete and the like, which devices are operable either by power or by hand.

It is an important object of my invention to provide a simple and easily constructed device of this character which is distinguished by low cost and efficiency in operation.

It is also an important object of my invention to simplify devices of this general nature, and to give them more efficient operation and render them capable of superior results, while reducing the effort and cost involved in the operation thereof.

Other objects and advantages of my invention will be apparent from a reading of the following description, taken in connection with the drawings, wherein for purposes of illustration I have shown a preferred embodiment of the invention.

In the drawings:—

Figure 1 is a general side elevational view of said preferred embodiment.

Figure 2 is a top plan view of Figure 1.

Figure 3 is a sectional elevational view from one end of Figure 1.

Figure 4 is a horizontal sectional view through Figure 1.

Referring in detail to the drawings, wherein like numerals refer to like parts throughout the same, the numeral 5 generally designates the mixing receptacle and the numeral 6 generally refers to the rocker support therefor whereby the receptacle 5 may be given the desired rocking motion for turning over and mixing therein a charge of concrete forming materials or the like and water or other fluid.

The receptacle 5 is of generally rectangular elongated box-like formation provided with a comparatively narrow transversely elongated opening 7 disposed centrally and intermediate the ends of the top of the receptacle. One side 45 of the receptacle is angularly and outwardly expanded as indicated at 8 and in this side there is provided a spout structure 9 for discharging the contents of the receptacle. The spout has the top plan view seen in Figure 2 and is composed of convex walls 10 having an upward inclination as shown in Figures 1 and 2. The upper edges of the walls of the spout slope downwardly and outwardly as indicated at 11 to a level below that of the top of the receptacle.

At each end of the container the end wall is semi-circularly curved as indicated at 12 and 13, and the side walls 14 and 15 of the receptacle are appropriately curved and connected to the ends 12, 13 by welding or other suitable construction. The curved ends of the receptacle are provided properly shaped and proportioned so that when there is a concrete mix in the receptacle it and the ingredients thereof will be thrown toward one end thereof when the receptacle is rocked and thrown upwardly and inwardly and turned over and when the receptacle is rocked in the opposite direction, the mix is turned over at the other end of the receptacle, thus thoroughly mixing together and turning over the concrete mix, whereby to thoroughly integrate the ingredients thereof and produce a good grade of concrete or the like.

The rocker structure 6 comprises a pair of semi-circularly curved bars 16, 17 transversely spaced and extending at either end to a point at either end of each longitudinal side of the receptacle near the inward terminals of the curvate portions 12, 13. Each end of the rockers 16, 17 has a vertically projecting member 18, 19 and 20, 21. These vertical members are connected in any suitable manner to the outside of the longitudinal sides of the receptacle and extend thereabove as indicated in the drawings, whereby to constitute handles for manually 85 rocking the device of the invention when employing it for mixing concrete or the like, and for assisting in the tilting of the device for discharging concrete or the like therefrom from the spout 90.

The semi-circularly curved rockers 16, 17 may be formed of round stock and the vertical members 18, 19 and 20, 21 formed by flattening end portions of such round stock.

Vertical braces 22, 23 are connected between 95 middle portions of the rockers 16, 17 and the bottom of the receptacle, and between these braces 22, 23 and connected thereto at upper and lower portions thereof are crossed brace bars 24 which have their ends angularly turned and secured as indicated at 25 to the said portions of the braces 22, 23, whereby to give the rocker structure rigidity adequate for requirements.

It is important that it be understood that when the sand, cement, and water of a typical concrete mix or the like is placed into the receptacle through the opening 7, the mix will be properly agitated and mixed when it is caused to run alternately to one end and the other of the receptacle by rocking the receptacle, so that 110

the curved formation 12, 13 will throw the mix up-side-down. Repeated rockings of the device of the invention will bring about the desired mixture and consistency of the concrete mix or the like.

It will be obvious that the simplicity, low cost of manufacture, and ease of operation referred to in the beginning of this specification are attained in an outstanding degree.

10 Though I have shown and described herein a preferred embodiment of the invention, it is to be definitely understood that I do not desire to limit the application of the invention thereto, and any change or changes may be made in 15 materials and in structure and arrangement of parts within the spirit of the invention and the scope of the subjoined claims.

What is claimed is:—

20 1. A mixer of the type described comprising a closed receptacle having a flat bottom and vertically and inwardly curved ends, and provided centrally of its top with a relatively narrow transverse charging opening extending through one side of the receptacle, a discharge 25 spout laterally extended from said side of the receptacle and in communication with the charging opening, rocker means for rockably supporting the receptacle, said mixer being rockable for throwing a charge against either curved 30 end thereof for turning over and mixing the charge.

2. A mixer of the type described comprising a closed receptacle having vertically and in-

wardly curved ends, and provided centrally of its top with a charging opening, a discharge spout laterally extended from one side of the receptacle and in communication with the charging opening, rocker means for rockably supporting the receptacle, said mixer being rockable for throwing a charge against either curved end thereof for turning over and mixing the charge, said rocker means comprising a pair of curved elements having at either end an upper portion secured to the side of the receptacle, the upper portions being extended above the receptacle and forming handles for rocking the receptacle for mixing and for tilting the receptacle for discharging by the spout.

3. A mixer of the type described comprising a closed receptacle having vertically and inwardly curved ends, and provided centrally of its top with a charging opening, a discharge spout laterally extended from one side of the receptacle and in communication with the charging opening, rocker means for rockably supporting the receptacle, said mixer being rockable for throwing a charge against either curved end thereof for turning over and mixing the charge, said rocker means comprising a pair of curved elements having at either end an upper portion secured to the side of the receptacle, vertical braces connected between the curved elements and the receptacle, and crossed braces secured to and between the vertical braces.
